UNITED STATES PATENT OFFICE.

MATTHEW H. LOUGHRIIDGE, OF BOGOTA, NEW JERSEY.

RAILWAY SIGNAL AND TRAIN-CONTROL SYSTEM.

Application filed July 23, 1922. Serial No. 576,822.

This invention relates to railway signal and train control systems and has for an object to increase the safety of systems of this kind by controlling the train according to speed and conditions of the block. More particularly this invention relates to a novel type of track magnet used for systems of this kind for inductively operating devices on a locomotive and the use of devices on a locomotive responding inductively to the track device, the action of this device being amplified by mechanical motion. The invention also includes a system of speed control operated by a centrifuge in combination with a timing device, and it further includes a novel method of manually releasing the brakes after the apparatus has become effective to control the train. The system further includes a method of manually suspending its operations during the time a locomotive passes from one track device to the next.

These, and other objects of the invention will be understood from the following specifications, and the accompanying drawings in which Figures 1 and 2, show in detail the construction of the track magnet. Figures 3, and 4, show the relative location of the locomotive apparatus to the track apparatus. Figure 5 shows the relation between the poles on the locomotive apparatus and the rail of a turn out switch. Figures 6, 7 and 8, show a type of centrifuge used in connection with this invention. Figure 9, shows the arrangement of the locomotive apparatus. Figure 10, shows the relative arrangement of the track apparatus with respect to Figure 9. Figure 11 shows one method of controlling the track apparatus and Figure 12 shows certain details relating to the manual cut out apparatus.

This invention may be applied to provide a plain stop, or a stop with speed control, or cab signals with speed control according to the extent to which the installation is carried out. The system is shown as operated inductively, that is, by obtaining the effects between the track apparatus and the locomotive apparatus by electro-magnetic induction. However, the various elements and principles of the invention may each be applied independently with any system of train control and are not intended to be applied solely with the system as herein disclosed.

The track magnet is constructed to be

clamped against the running rail without drilling or preparing this rail in any manner, thereby greatly facilitating installation and insuring alignment between the running rail and the track magnet. A proceed effect is transmitted to a locomotive when the track magnet is energized by the passage thereover of a magnetic amplifier. This is a device to which mechanical motion is applied for rotating an armature at high speed. The field for this armature is supplied by the track magnet, so that a current of considerable voltage is generated by the armature when the track magnet is energized. This device, therefore, acts both as a detector and amplifier of the inductive effect induced by the track magnet.

The stop effect is produced inductively from one pole of the track magnet which aligns with poles of an amplifier on the locomotive. This amplifier is energized by a magnet coil and has an armature rotating in a field with a wide air gap. When the poles pass over the track member the magnetic field through the armature is thereby suppressed, thus practically de-energizing the circuit controlled by the armature and leading to a stop application of the system, unless the proceed amplifier has been energized to produce a proceed effect.

A centrifuge is used with this invention which has a continuous means of detecting its own failure whether it is rotating or at rest. This means consists in applying air pressure to the rotating parts of the centrifuge in such a manner that if any of its parts become broken or disconnected the air will escape. The air supply for this purpose may be taken from the train line and an escape of air will thus lead to the application of the train brakes.

In the application of the system, when a caution signal is received the brake apparatus is brought into effect. However, a restraining means is provided which prevents the brake apparatus from controlling the train until after the lapse of a pre-determined time interval, so that upon receiving a caution signal the engineman may take steps to control the train manually and if he reduces speed below a pre-determined value the train control system will not become effective. This is secured by the application of a timing cylinder co-operating with the centrifuge device and the cab

signal, so that the air in this cylinder must be exhausted before the braking apparatus becomes effective.

- 5 In systems of this kind, after a train has been brought under control it is desirable that the control may be manually released and the train proceed. However, a manual release of this type must be so constructed that it cannot be prematurely moved to the 10 released position. This I secure in the present invention, by the use of a stepping-valve connected with the train braking system, and operated automatically by the cab signal and the centrifuge as herein described.
- 15 Co-operating with this stepping valve is the manual release valve. These two valves are provided with two independent air conduits. The ports are alternately placed in staggered relation to each other so that the 20 passage through one air conduit is closed when the other is opened. The arrangement is such that each movement of the stepping valve requires the release valve to change positions in order to release the 25 brakes, but if the release valve is prematurely moved before the stepping valve it will lead to the application of the brake.

The system herein described provides manual means located at two different points 30 on the locomotive for suspending or cutting the system out of operation. This manual suspension, however, is automatically cancelled as soon as the first track device has been encountered. That is to say, when entering side tracks or any protected territory 35 the engine crew may arrange to suspend operation of the system, but it automatically becomes operative again when the locomotive re-enters protected territory.

- 40 Referring to the drawings, Figures 1, and 2, showing the track magnet, the rail is indicated by 11, the wheel of the locomotive by 12, and the magnet itself by 13. One pole of the track magnet is shown by plate 45 14, and the other pole by the angle iron 15. Magnet coils 16 are placed between plate 14 and 15 upon bolt 24, which forms a core for the magnet and has a pole piece 25 secured to the pole 15, at 26; 17 indicates 50 a conduit that may be used for the electric conductors controlling magnet coils 16.

This magnet is clamped to the rail 11 by the clamp 18, and the hook-bolts 19, engaging the flange of the rail as shown. The 55 clamp 18, is formed with pads to grip the flange of the rail and the portion 20 forms a solid piece upon which the plate 14 rests. Seated on clamp 18, are the non-magnetic brackets 22, also secured by the hook-bolts 19. These brackets are flared as shown, and 60 screwed to the angle iron 15, at 23 by rivets or bolts. This track magnet may have any number of magnet coils and may be made of any convenient length. However, about 65 three coils will be sufficient for operating

the locomotive apparatus under ordinary conditions. The construction is such that the coils or, in fact, any part of the magnet may be readily removed without disturbing the remaining parts.

70 The locomotive apparatus is shown in Figure 3, in which the bracket 28, is secured to the axle box 27 of the wheel 12, and supports the proceed amplifier, 29, in the position relative to the track magnet as indicated 75 in Figure 4, with the pole piece 34 aligning with the rail head and the pole piece 35 aligning with angle iron 15. When 14 and 15 are magnetized it is apparent that in this 80 position a flux will be driven through the field of the amplifier 29, which otherwise remains deenergized.

The stop amplifier indicated at 30, is suspended by hangers 31 from the axle box 27, and has poles 32 and 33 aligning with outer 85 member 15 of the track magnet 13, thereby establishing a path for lines of force between poles 32 and 33 through this track member. This condition causes the stop effect. It will be noted that at turnout switches the poles 90 32 and 33 pass over the turnout rail which would in itself become a conductor of the lines of force and thereby tend to cause a false stop operation. To guard against this 95 possibility, I shape the poles 32 and 33, with pointed ends as indicated by Figure 5, in which the stock rail is indicated by 11, and the switch rail by 11^a. If a train is running on 11^a these poles will cross stock rail 11, as shown. However this rail turns 100 out at an angle to the running rail and when the poles are pointed as shown, a comparatively small area is provided for conducting the lines of force between these poles, so that the magnetic field is not suppressed to 105 such an extent as would cause a stop effect, and where desired the stock rail may be constructed of non-magnetic material such as manganese steel, and the pole 15, may be arranged on a higher elevation than the running rail thereby increasing the air gap between the track rails and the poles of the 110 amplifier.

The centrifuge.

115 The centrifuge is preferably supported by an arm 55 pivoted to the frame or pilot of the locomotive 53 by the bracket 54. This arm may be constructed in the form of a frame as shown in Fig. 7 with spacers 59 to 120 hold the sides rigidly together. The end of this arm carries the mechanism with the friction wheel 56 engaging the running wheel 52 and is held in engagement therewith by the compression spring 58 acting against the 125 outer extremity 57 of arm 55.

The centrifuge mechanism is enclosed in the case 61 secured to the arms 55. This case supports the ball bearings 62 and 63 for the shaft 64 of the friction wheel 56. 130

These bearings align with the arms 55—55 to relieve the case from the strain. Mounted on shaft 64 is the bracket 66 pivotally supporting a pair of arms indicated by 67, and the other end of the shaft has a bracket 69 arranged to slide thereon which pivotally supports a pair of arms indicated by 68. The arms 67 and 68 are pivotally joined to support the disc weights 70 as shown in

10 Fig. 6. A coil spring 71 tends to hold the brackets 66 and 69 apart while the weights 70 by centrifugal action tend to spread out and bring these brackets towards each other according to the usual construction of centrifugal devices. The bracket 69 slides on the shaft 64 proportionally to the speed of the shaft and carries arm 72, pivoted at 73 in bracket 74 with it. The arm 75 moves simultaneously with arm 72 and engages plunger 20 76 moving in valve seat 77 to control an air supply for operating the system. When the valve plunger is in the position shown a passage is established from the air supply pipe 84, through 83, port 82 and connection 25 80 to pipe 81; thus pipe 81 is supplied with air at pressure when the centrifuge is at rest, this pipe being known as the centrifuge pipe. When a certain predetermined speed is attained the plunger 76 is moved to close 30 port 82 and to cause the D-valve 78 to connect the passage 80 with the exhaust port 79, thus releasing the air pressure from pipe 81 at high speed.

The position where the ports controlled by 35 plunger 76 operate can be adjusted by changing the position of valve seat 77. This is done by the threaded bushing 85 in the arm 55 which can be screwed out or in carrying the valve seat with it and is held in position 40 by the lock nut 86.

A cap 90 is placed on the end of shaft 64 and held in position by screw ring 91. A passage 92 connects this cap with the air supply pipe 84 and aligns with a groove on 45 the end of the shaft as shown. This groove communicates by opening 93 with the hollow centre of the shaft 94 and through the nut 65 which holds the friction wheel on the shaft, to the hollow chamber 95 enclosed 50 by the plate 96 in front of the friction wheel. Also, it will be noted that in bracket 66 a hollow passage 97 connects with the passage 94 and through the pivot supports to the 55 hollow passage 98 in arms 67 to the passage 99 at the ends of these arms which passage is stopped by the weights 70 as best shown in Fig. 6. With this construction it will be noted that an air pressure may be maintained on the rotating shaft, the friction 60 wheel, the weights and their connections both when the centrifuge is running and when it is at rest without interfering with its operation. Devices heretofore used with 65 systems of this kind driven by the movement of the vehicle did not embody the means of

detecting their own failure and their use has therefore been regarded as unsafe. With this invention, if any of the moving parts are broken or out of place, there will be an air leakage which will detect the defect. If 70 this air supply is connected with the train line, the leakage will lead to an application of the braking system and thus produce a condition of safety.

The air pipe 84 may be secured to arm 55 75 as indicated at 84^a Fig. 8 connecting to the locomotive frame near the pivot of this arm. Thus if this arm itself should become broken or displaced this will lead to a rupture of the air pipe and hence the trouble will be 80 instantly detected.

The track wiring.

Any of the established arrangements in block signaling may be used for wiring the 85 control of the track magnets. A typical arrangement is shown in Fig. 10, where the track rails are indicated by 11, and a track relay is indicated by 41 operated by the track battery 42 at the opposite end of the 90 block. One track magnet is indicated by 44 controlled by wire 45 through contact 46 of relay 41 to the battery connection indicated by B. This magnet is thus controlled by traffic conditions in the first block in advance 95 of the magnet. Magnet 47 is controlled by wire 48 through contact 49 of relay 43 to battery. Relay 43 is controlled by wire 40 and by the track relays for the first and second blocks so that magnet 47 is controlled 100 by traffic conditions in the first and second blocks in advance of the magnet. This arrangement is repeated at each block location.

The locomotive wiring.

Referring to Fig. 9, 101 represents a battery controlled by switch 102 and energizing mains 104 and 105. These mains energize duplicate sets of apparatus on either side of the locomotive and which are indicated by similar reference characters. These comprise the motor 106 continuously driving the armature 111 of the proceed amplifier 29, and motor 107 continuously driving the armature 112 of the stop amplifier 30. The 110 field coil 110 of the stop amplifier is also connected across these mains by wires 108 and 109.

The "flipper" 121 has an armature 122 capable of taking up either of two positions 115 when its field is energized. One of these positions raises the connection 123 to the walking beam 124 to the centre of which beam the rod 125 is connected for operating the signal 126. Also from the centre of this walking beam a rod 127 is connected for operating the plunger 128 of pin valve 129 to bring the train controlling mechanism into 125 operation.

When the signal is clear as shown, a pas-

sage is established from the air supply pipe 176 and 130 through a port in plunger 128 to signal pipe 131 and to cylinder 132 of the brake operating mechanism. This raises the piston 133 against the action of spring 134 and raises one end of walking beam 135. The rod 136 connects to the centre of this walking beam and through slot 140 engages pin 141 in lever 142. The outer end of this lever has a spring controlled dog 143 engaging the stepping wheel 144 which operates the brake controlling mechanism. Centrifuge pipe 81 connects to cylinder 137 and air pressure in this pipe raises piston 138 against spring 139 thus raising the opposite end of walking beam 135. Under a clear signal the centrifuge does not affect the brake mechanism and under low speed a caution or stop signal does not affect the brake mechanism.

Each step of wheel 144 operates a valve which will apply the brakes. This wheel is stepped by the downward movement of rod 136, the lost motion in slot 140 however being equivalent to the downward movement of either piston 134 or 138; this lost motion must be taken up before the wheel is moved. If a caution signal is received, cylinder 132 is exhausted by the D-valve in plunger 128 connecting pipe 131 with pipe 154 and whistle 155 is sounded from the air pressure in cylinder 132. This lowers piston 133 and takes up the lost motion in 140 so that wheel 144 will be moved when the centrifuge pipe 81 is exhausted. This pipe is exhausted when a predetermined speed is exceeded and under these conditions the wheel 144 is operated in response to the movement of piston 133. In order that speed control may not become effective immediately that a caution signal is received pressure is maintained in cylinder 132 for a time interval after the valve 129 has operated to exhaust this cylinder. This pressure is obtained from the reservoir 151 connecting by pipe 152 through ball valve 153 with cylinder 132 which exhausts through this cylinder and sounds whistle 155. At the end of this time interval, if speed is not below the predetermined amount the brake mechanism will be operated.

When pressure is restored in either cylinder, rod 136 is raised and spring 148 raises lever 142 against a stop and brings 143 into engagement with a new tooth of wheel 144 placing the mechanism in position for the next operation; thus while a caution signal is continued a predetermined speed must not be exceeded. When running at low speed it is apparent that piston 138 is raised and a caution signal does not affect the braking mechanism. When a clear signal is received, pressure is applied to cylinder 132 and pressure is gradually renewed in reservoir 151 through pipe 152 and valve 153.

Attention is called to the fact that the braking mechanism is operated by exhausting air from cylinders 132 and 137 and therefore a leak in these connections will lead to a brake operation.

In the application of train control to the braking system of a locomotive considerable variation is required due to the different classes of traffic; and at the present time there is considerable difference of opinion as to the extent to which the control should be effective. In the present instance it is assumed that the engineman, after performing a specific act, will follow this up by reducing speed to safe running conditions. For instance, when valve 144 is moved to control the train, this control can immediately be rendered ineffective by the engineman operating the release handle 147. In doing so, however, he is reminded that a reduction in speed is necessary and should thereupon control his train below the predetermined speed. Where the engineman cannot be relied upon to properly control the train the releasing handle may be located on the running board so that it is inaccessible except at low speeds, or a slow releasing mechanism, such as shown in U. S. Patent 1,299,595, may be associated with the releasing handle thereby preventing release of the control until after the lapse of a given time interval.

The field of the "flipper" 121 is energized by the armature of the stop amplifier connecting by wires 159 and 160 to coil 161. The armature 122 is positioned by the proceed amplifier through a circuit established from armature 111, wires 156, coil on armature 122, coil 158 on field and wire 157 to armature 111. When the proceed amplifier is energized coil on armature 122 and the field is energized causing this armature to take up the position to give a clear signal as shown and as long as coil 161 is energized this armature will be held in this position. When coil 161 is deenergized, armature 122 is biased to lower connection 123 and gives a caution signal and will remain in this position when coil 161 is reenergized and until moved to the clear position by the proceed amplifier as described. The locomotive is provided with two sets of amplifiers and flippers, one on either side as shown with similar reference characters and the track is provided with two sets of magnets to correspond with the locomotive apparatus as shown in Fig. 10.

Releasing apparatus.

When a train has been brought under control it is desirable to release the brakes manually and proceed under caution. This requires a manual release which must be so constructed that it cannot be prematurely operated to anticipate a brake application.

This is provided for in the release shown in Fig. 12 where the wheel 144 operates the stepping valve 181 and the valve 182 is operated by the handle 147, these valves and 5 connections being housed in a suitable casting 146. The valve casing 146 has a central opening under the stepping valve 181 which connects with pipe 177. This pipe is part of the braking system of the locomotive and 10 may be connected with the equalizing reservoir of the air brake system or otherwise used to apply the brakes. A row of ports is provided in the top of this valve connecting with pipe 177 also a similar row of 15 ports in staggered relation to the top row is provided in the lower section of this valve. Valve 182 has one port in the top section and a port in the lower section angularly displaced from the top port; these ports 20 communicate with the interior of the valve which leads to the exhaust. A conduit 178 extends between valves 181 and 182 and aligns with the top ports and a conduit 179 similarly aligns with the lower ports. Since 25 the ports are staggered and the conduits are on the same vertical plane it is apparent that the passage to only one conduit can be open at each valve at once. In order to prevent pipe 177 from exhausting valve 182 30 must be moved in synchronism with valve 181. When valve 181 moves, for instance, to open the passage to conduit 178, it closes the passage to conduit 179, but valve 182 must be moved to close 178 and this position 35 opens the passage to 179 so that the next movement of 181 will open 179 and close 178 and require valve 182 to be moved back again closing 179 and opening 178. Thus valve 182 must be moved for each movement 40 of valve 181 and if moved without a corresponding movement of 181 it will exhaust pipe 177. The release 147 may be placed on the running board so that it is not readily accessible when a train is running at speed. 45 When running on side tracks there are, of course no track magnets and no control is necessary; it may be desirable in this case to suspend the operation of the system with however the assurance that it will become 50 effective immediately the train reenters protected territory. I provide for this condition by the use of a flipper 164 having an armature 168 with connection 169 and connection 172 to a crank arm pivoted at 174 and carrying the disc 173 which may be moved into 55 position to cover signal 126; also connection 170 operating valve 171 preventing the escape of air from cylinder 132 and prevent the operation of whistle 155. This flipper 60 is operated by the stop amplifiers, the field coil 163 being energized by connection to wire 160 controlled by switch 161' and wire 162 to wire 159. This flipper is positioned to 65 cutout the system by switch 165, wire 166, coil on armature 168, field coil 168a and wire

167. After armature 168 is moved to the cut-out position it will remain in this position while coil 163 is energized; as soon however, as the first track magnet is encountered the 70 stop amplifier is deenergized, the flipper 164 is deenergized and it takes up the position of its bias to remove the cutout. The operation of switch 165 deenergizes coil 161 giving a caution signal. Switches 161' and 165 75 should, preferably, be operated by different individuals at the same time.

With this system it will be noted that no relays or moving contacts are used and that the inductive effect between the track and the locomotive is obtained with a high degree 80 of efficiency.

In operation, the amplifier 29 runs idle until an energized track magnet aligns with the poles of the amplifier; this supplies the magnetic field for the rotating armature with the result that a current is generated in wires 156 and 157 which produces the proceed effect.

The stop amplifier 30 runs continuously 90 and generates a current in the armature 112 as it rotates in the field created by coil 110. When the extended poles align with the outer pole of the track magnet the field created by the coil 110 is substantially deflect- 95 ed from the armature 112 by the flux finding a path through the iron pole of the track magnet, which becomes in effect, an armature for the coil 110. The flux in this case is at right angles to the flux created by the magnetizing coil 16 so that there is no conflict- 100 ion between these two magnetic conditions. The circuit, therefore, from armature 112 is substantially deenergized when the stop amplifier runs over the pole of a track magnet 105 whether this magnet is energized or not.

It will be noted that the semaphore indicator 126 connected with the walking beam 124 is capable of giving indications in the horizontal, the 45 degree and the vertical positions, corresponding to stop, caution 110 and clear indications. As shown in Fig. 9, the train controlling mechanism associated with valve 129 is arranged to function as soon as the caution signal is established and thereby insure that a predetermined 115 speed shall not be exceeded under caution conditions. It is apparent that if the train control is to be applied to a greater extent that it is necessary only to provide another valve corresponding to 129 arranged to set 120 up the controlling conditions under a stop signal and which would be a duplicate of the apparatus shown and operating in the manner described.

Having thus described my invention, I 125 claim:

1. In a train control system, the combination of a track with a vehicle thereon, magnets located on said track at intervals for inductively operating a device on said ve- 130

- hicle, said magnets comprising elongated poles with energizing coils between said poles, said magnets being clamped to the rail of said track and one of said poles being supported by a non-magnetic bracket. 5
2. In a train control system, the combination of a track with a vehicle thereon, magnets located on said track at intervals for inductively operating a device on said vehicle, said magnets comprising elongated poles with energizing coils between said poles, one pole consisting of a plate abutting against the rail of said track, said magnet secured to said rail by hook bolts. 10
15. 3. In a train controlling mechanism, the combination of a track with a vehicle thereon, a centrifuge on said vehicle associated with said train control system and means embodied in said centrifuge independent of 20 the normal operation of said centrifuge for automatically detecting when the driving mechanism of said centrifuge breaks down.
4. In a train control system, the combination of a track with a vehicle thereon, a 25 centrifuge on said vehicle driven by the movement of said vehicle on the track, said centrifuge associated with said train control system and an air supply connected by a dead ended connection with the moving 30 parts of said centrifuge.
5. In a train control system, the combination of a track with a vehicle thereon, a centrifuge driven by the movement of said vehicle on the track, said centrifuge associated with said train control system, a hollow shaft without an outlet for said centrifuge and an air supply connected with 35 said hollow shaft.
40. 6. In a train control system, the combination of a track with a vehicle thereon, a centrifuge associated with said train control system and driven by the movement of said vehicle, a hollow shaft and a hollow driving wheel for said centrifuge and an air supply connected with said shaft and driving wheel.
45. 7. In a train control system, the combination of a track with a vehicle thereon, a centrifuge associated with said train control system and driven by the movement of said vehicle, said centrifuge having weights responsive to speed and a hollow connection for said weights, and an air supply connected with said weights. 50
55. 8. In a train control system, the combination of a track with a vehicle thereon, a centrifuge connected with said train control system and driven by the movement of said vehicle, and a dead ended passage connecting the moving parts of said centrifuge, said passage connected with the braking system of said vehicle. 55
60. 9. In a train control system, the combination of a track with a vehicle thereon, a mechanism driven by the movement of said 65
- vehicle and associated with said train control system, and a dead ended passage connecting the moving parts of said mechanism, said passage connected with an air supply. 70
10. In a train control system, the combination of a track with a vehicle thereon, a mechanism driven by the movement of said vehicle and associated with said train control system, a pivoted arm supporting said mechanism and an air pipe secured to and moving with said pivoted arm. 75
11. In a train control system, the combination of a track with a vehicle thereon, a mechanism having a friction wheel, said wheel engaging the running wheel of said vehicle and driven thereby, a space in said wheel and means for maintaining an air pressure in said space. 80
12. In a train control system, the combination of a track with a vehicle thereon, a mechanism supported by a pivoted arm and having a friction wheel driven by the running wheel of said vehicle, a space in said wheel and an air pipe secured to said arm and connected with the space in said wheel. 85
13. In a train control system, the combination of a track with a vehicle thereon, a centrifuge driven by the movement of said vehicle and associated with said train control system, an air supply pipe connected with a dead ended passage in said centrifuge, a control pipe connected with said centrifuge and a valve controlled by said 90 centrifuge for varying the pressure in said control pipe. 95
14. In a train control system, the combination of a track with a vehicle thereon, a magnetic member on said track having a pair of poles, a generator on said vehicle having a rotating armature in a magnetic field, poles of said field aligning with one pole of said track member, a translating device connected with said armature and means for varying the operation of said device when said poles come under the influence of said track member. 100
15. In a train control system, the combination of a track with a vehicle thereon, a magnetic member on said track having a pair of poles, and a generator on said vehicle having an armature and poles creating a field, said poles aligning with one pole of said track member, the air gap between said armature and said poles being enlarged to an extent comparable with the air gap between the track member and the poles, whereby the field through said armature is suppressed when said poles come under the influence of said track member, said armature associated with said train control system. 115
16. In a train control system, the combination of a track with a vehicle thereon, a 120
- 125
- 130

- 5 magnetic member on said track having a pair of poles, a generator on said vehicle associated with said train control system, an armature and a field coil for said generator and poles extending from the field of said generator to align with one pole of said track member whereby the flux is shunted from said armature by said track member.
- 10 17. In a train control system, the combination of a track with a vehicle thereon, a magnetic member on said track, and a generator on said vehicle associated with said train control system, poles of said generator arranged to align with said track member, said poles pointed at their ends.
- 15 18. In a train control system, the combination of a track having turn-out switches, a vehicle on said track, a magnetic member on said track, and a device on said vehicle having poles aligning with said track member and associated with said train control system, said poles shaped so as not to align with the rail of said turn-out switches.
- 20 19. In a train control system, the combination of a track with a vehicle thereon, said track divided into blocks and having devices thereon controlled by said blocks, devices on said vehicle responsive to said track devices, a centrifuge and a braking mechanism on said vehicle, a cylinder having a piston controlled by said vehicle devices and a second cylinder having a piston controlled by said centrifuge, said pistons 25 cooperatively operating said braking mechanism and means associated with one of said cylinders for retarding the movement of its piston.
- 25 20. In a train control system, the combination of a track with a vehicle thereon, said track divided into blocks and having devices thereon controlled by said blocks, devices on said vehicle responsive to said track devices, a speed responsive device and a 30 braking mechanism on said vehicle, a cylinder having a piston controlled by said vehicle devices and a second cylinder having a piston controlled by said speed responsive device, said pistons cooperatively operating said braking mechanism and a device associated with one of said cylinders for retarding the movement of its piston.
- 35 21. In a train control system, the combination of a track with a vehicle thereon, a braking mechanism on said vehicle, a speed responsive device and a timing device on said vehicle associated with said train control system, said speed responsive device operating a piston in a pneumatic cylinder 40 and said timing device operating a piston in a second cylinder, said pistons cooperatively operating said braking mechanism and a ball valve for adjusting said timing device.
- 45 22. In a train control system, the combination of a track with a vehicle thereon, a magnet on said track, and a plurality of devices on said vehicle having moving elements, said devices arranged to be inductively influenced by said track magnet, one of said devices energized by said track magnet and the other device deenergized by said track magnet, said moving elements associated with said train control system.
- 50 23. In a train control system, the combination of a track with a vehicle thereon, a magnet on said track, and a plurality of devices on said vehicle having rotating elements, said devices arranged to be inductively influenced by said track magnet, one of said devices receiving a stop effect from said magnet and the other device receiving a proceed effect from said track magnet.
- 55 24. In a train control system, the combination of a track with a vehicle thereon, a magnetic device on said track having a pair of poles, a device on said vehicle having a continuously moving element and an energized coil, a circuit associated with said moving element to maintain a proceed condition on said vehicle and means whereby said circuit is deenergized when said vehicle device comes under the influence of one pole of said track device.
- 60 25. In a train control system, the combination of a track with a vehicle thereon, devices on said track and a device on said vehicle responsive to said track devices, and a braking mechanism on said vehicle controlled by said device, said mechanism comprising a stepping valve having a plurality of operative positions to apply the brakes.
- 65 26. In a train control system, the combination of a track with a vehicle thereon, devices on said track and a device on said vehicle responsive to said track devices, a braking mechanism on said vehicle controlled by said device, said mechanism comprising a stepping valve having a plurality of positions to apply the brakes and manually operated means for preventing the application of the brakes.
- 70 27. In a train control system, the combination of a track with a vehicle thereon, devices on said track and a device on said vehicle responsive to said track devices, a braking mechanism on said vehicle controlled by said device, said mechanism comprising a stepping valve having a plurality of positions to apply the brakes and a manually operated valve having a plurality of positions for preventing the application of the brakes.
- 75 28. In a train control system, the combination of a track with a vehicle thereon, devices on said track and a device on said vehicle responsive to said track devices, a braking mechanism on said vehicle controlled by said device, said mechanism comprising a valve having a plurality of positions to apply the brakes and a release valve.

- having a plurality of positions to prevent application of the brakes and means whereby said valves must be operated in synchronization to prevent application of the 5 brakes.
29. In a train control system, the combination of a track with a vehicle thereon, devices on said track and a device on said vehicle responsive to said track devices, a 10 braking mechanism on said vehicle controlled by said device, said mechanism comprising an operating valve having a plurality of positions to apply the brakes and a release valve for preventing the application 15 of the brakes, a plurality of conduits between said valves and means whereby when one conduit is closed the other is open.
30. In a train control system, the combination of a track with a vehicle thereon, devices on said track and a device on said vehicle responsive to said track devices, a 20 braking mechanism on said vehicle controlled by said device, said mechanism comprising an operating valve having a plurality of ports in staggered relation and a release valve having a plurality of ports in 25 staggered relation and a plurality of conduits connecting said ports.
31. In a train control system, the combination of a track with a vehicle thereon, a 20 magnet on said track for operating a device on said vehicle, said magnet comprising a pair of poles with energizing means between 30 said poles and a non-magnetic bracket for supporting one of said poles.
32. In a train control system, the combination of a track with a vehicle thereon and a magnet on said track cooperating with a device on said vehicle, said magnet comprising 40 a pair of poles with energizing coils between said poles, one of said poles consisting of an elongated magnetic member located in contact with and level with the head of the track rail.
33. In a train control system, the combination of a track with a vehicle thereon, a magnet on said track cooperating with a device on said vehicle, said magnet comprising an elongated magnetic member placed substantially in contact with the head of the 50 rail and a support for said member directly interposed between said member and the flange of said rail.
34. In a train control system, the combination of a track with a vehicle thereon, a magnet on said track cooperating with a device on said vehicle, said magnet comprising an elongated magnetic member located close to the head of the running rail and a bracket 55 for said magnet, said bracket secured to said rail and directly interposed between said member and the flange of said rail.
35. In a train control system, the combination of a track with a vehicle thereon and a magnet on said track cooperating with a 60 device on said vehicle, said magnet comprising a pair of poles parallel with said track and an energizing coil between said poles, one of said poles consisting of an elongated angle iron with the horizontal leg of the 65 angle extending over said coil.
36. In a train control system, the combination of a track with a vehicle thereon, a magnet on said track cooperating with a device on said vehicle, said magnet comprising a pair of poles with energizing means between 70 said poles, means for clamping both of said poles to the rail of said track and means for magnetically insulating one of said poles from said rail.
37. In a train control system, the combination of a track with a vehicle thereon, a magnet on said track cooperating with a device on said vehicle, said magnet comprising a pair of poles, a bracket clamped to a rail 75 of said track supporting one of said poles and a second bracket secured to the first bracket supporting the other pole.
38. In a train control system, the combination of a track with a vehicle thereon, a magnet on said track cooperating with a device on said vehicle, said magnet comprising a pair of poles, a bracket supporting one of 80 said poles secured by bolts to a rail of said track and another bracket secured by the same bolts supporting the other pole of said magnet.
39. In a train control system, the combination of a track with a vehicle thereon, a magnet on said track cooperating with a device on said vehicle, said magnet comprising a pair of poles with a plurality of energizing 85 means in spaced relation between said poles and a non-magnetic bracket placed intermediate said energizing means supporting one 90 of said poles.
40. In a train control system, the combination of a track with a magnet thereon, said magnet comprising a longitudinal plate, uniform in section with one edge bearing on 95 the flange of the rail and the other edge placed against the head of and flush with the top of the running rail and means connected with the side of said plate for magnetizing said plate.
41. In a train control system, the combination of a track with a vehicle thereon, a centrifuge associated with said train control system, said centrifuge having a driving wheel connected with the running gear of 100 said vehicle, a chamber in said wheel connected with an air supply and a detachable cover for said chamber.
42. In a train control system, the combination of a track with a vehicle thereon, a 105 centrifuge associated with said train control system, said centrifuge having a driving wheel connected with the running gear of said vehicle, a shaft with an air passage connected with said driving wheel, arms with 110

- an air passage connected to said shaft and means whereby a continuous passage is formed between said shaft and said arms.
43. In a train control system, the combination of a track with a vehicle thereon, a centrifuge driven by the movement of said vehicle, a shaft and driving gear associated with said centrifuge and an air passage maintained by the unity of said shaft and gear.
44. In a train control system, the combination of a track with a vehicle thereon, a centrifuge driven by the movement of said vehicle, a shaft for said centrifuge, a driving wheel mounted upon said shaft and an air passage maintained by the unity of said shaft and driving wheel.
45. In a train control system, the combination of a track with a vehicle thereon, a centrifuge driven by the movement of said vehicle, a hollow shaft for said centrifuge, a driving wheel mounted upon one end of said shaft, a cap enclosing the other end of said shaft and an air supply connected through said cap and said hollow shaft to said driving wheel.
46. In a train control system, the combination of a track with a vehicle thereon, a magnet on said track for inductively operating a device on said vehicle, horizontal energizing coils for said magnet having pole pieces and an angle iron bar having one leg secured to one of said pole pieces and the other leg extending over said coils.
47. In a train control system, the combination of a track with a vehicle thereon, a magnet on said track for inductively operating a device on said vehicle, energizing coils for said magnet, an angle iron bar forming one pole of said magnet and a bracket clamped to the track and arranged to support both legs of said angle iron.
48. In a train control system, the combination of a track with a vehicle thereon, a centrifuge associated with said train control system and including an air valve with a plunger, a valve seat for said plunger, means operatively connecting said plunger with said centrifuge and means for adjusting said valve seat relative to said plunger.
49. In a train control system, the combination of a track with a vehicle thereon, a centrifuge associated with said train control system and including an air valve with a plunger, means operatively connecting said plunger with said centrifuge and independent means tending to move said plunger to a position corresponding to the position to which said plunger is moved by said centrifuge when running at speed.
50. In a train control system, the combination of a track with a vehicle, a controlling mechanism on said vehicle comprising a brake operating device with an air cylinder having a piston, a track controlled element, a speed controlled element controlling said brake operating device, an air reservoir of limited capacity connected with said cylinder to delay the operation of its piston and an audible signal, said elements being so arranged as to operate said audible signal from said air reservoir independently of the control by said speed controlled element.
51. In a train control system, the combination of a track with a vehicle thereon, a controlling mechanism on said vehicle comprising a brake operating device and an air cylinder, a timing reservoir having a manually regulated valve connected with said air cylinder, a speed responsive device and an audible signal and means for sounding said audible signal and for retarding a brake operation from the pressure in said reservoir when a predetermined speed is exceeded.
52. In a train control system, the combination of a track with a vehicle thereon, a controlling mechanism on said vehicle comprising a brake operating device with a cylinder, a track controlled element, a speed controlled element, a timing reservoir with a manually regulated valve connected with said cylinder and an audible signal, means for operating said brake device by said track controlled element when a predetermined speed is exceeded and means including said timing reservoir for delaying said control and sounding said audible signal.
53. In a train control system, the combination of a track with a vehicle thereon, a controlling mechanism on said vehicle comprising a plurality of cylinders with plungers, each independently controlled and a brake valve directly operated by the combined movement of said plungers to apply the brakes.
54. In a train controlling system, the combination of a track with a vehicle thereon and a controlling mechanism on said vehicle, said mechanism comprising a stepping valve with a plurality of means for cooperatively operating said valve.
55. In a train controlling system, the combination of a track with a vehicle thereon and a controlling mechanism on said vehicle, said mechanism comprising a stepping valve with a plurality of means for operating said valve through a lost motion connection.
56. In a train controlling system, the combination of a track with a vehicle thereon and a controlling mechanism on said vehicle, said mechanism comprising a stepping valve with a plurality of independent means for cooperatively operating said valve.
57. In a train controlling system, the combination of a track with a vehicle thereon, a controlling mechanism on said vehicle, said mechanism comprising a valve with a plurality of independent means for operating

- said valve and a lost motion connection between said means and said valve equivalent to the operation of one of said means.
58. In a train controlling system, the combination of a track with a vehicle thereon, a controlling mechanism on said vehicle, said mechanism comprising a valve having a plurality of similar controlling positions and a plurality of independent means for holding said valve away from the controlling positions, one of said means controlled from the track and the other means controlled by the speed of the vehicle.
59. In a train controlling system, the combination of a track with a vehicle thereon, a controlling mechanism on said vehicle, said mechanism comprising a stepping valve, a plurality of plungers and a walking beam, said plungers operating said valve through said walking beam.
60. In a train controlling system, the combination of a track with a vehicle thereon, a controlling mechanism on said vehicle, said mechanism comprising a valve having an operative and an inoperative position and plungers arranged to hold said valve in the inoperative position, each of said plungers being capable of holding said valve in the inoperative position without regard to the movement of the other plungers.
61. In a train controlling system, the combination of a track with a vehicle thereon, a controlling mechanism on said vehicle, said mechanism comprising a valve having an operative and an inoperative position and a plurality of means arranged to mechanically move said valve to the operative position, said movement requiring the accumulated movement of all of said means.
62. In a train controlling system, the combination of a track with a vehicle thereon, a controlling mechanism on said vehicle comprising a stepping valve, each step of said valve operating to control said vehicle and means for stepping said valve.
63. In a train controlling system, the combination of a track with a vehicle thereon, a controlling mechanism on said vehicle comprising a rotary stepping valve rotating in one direction and having a controlling position for each step, each of said positions operating said mechanism to the same extent.
64. In a train controlling system, the combination of a track with a vehicle thereon, and a controlling mechanism on said vehicle, said mechanism comprising a stepping valve rotating in one direction, each step of said valve operating said controlling mechanism.
65. In a train controlling system, the combination of a track with a vehicle thereon, a controlling mechanism on said vehicle, said mechanism comprising a stepping valve with a lever, the downward movement of said lever moving said valve to the operating position and a plurality of means, each independently capable of preventing the downward movement of said lever.
66. In a train controlling system, the combination of a track with a vehicle thereon, a controlling mechanism on said vehicle, an automatic stepping device for operating said mechanism and a manually controlled stepping device cooperating with said automatic stepping device to prevent said operation.
67. In a train controlling system, the combination of a track with a vehicle thereon, a controlling mechanism on said vehicle, a device having a plurality of similar positions for operating said mechanism and a manually controlled device cooperating with the position of said first device to prevent said operation.
68. In a train control system, the combination of a track with a vehicle thereon, a controlling mechanism on said vehicle, a device having a plurality of similar positions for operating said mechanism and another device when moved to synchronize with the position of the first device preventing said control.
69. In a train control system, the combination of a track with a vehicle thereon, a controlling mechanism on said vehicle, a device having a plurality of similar positions for operating said mechanism and another device having a plurality of positions capable of being synchronized with the first device to prevent said operation.
70. In a train controlling system, the combination of a track with a vehicle thereon, a controlling mechanism on said vehicle, a device having a plurality of positions for similarly operating said mechanism, another device cooperating with the first device in operating said mechanism, a plurality of connections between said devices, and a source of energy controlled by said devices through said connections.
71. In a railway traffic controlling system, the combination of a track with a vehicle thereon, a device on said track controlled by traffic conditions, an indicator on said vehicle responsive to said track device, a source of energy on said vehicle for maintaining the indication of said device, a cancelling device on said vehicle for cancelling said indication and means for transferring the energy from said indicator to said cancelling device.
72. In a railway traffic controlling system, the combination of a track with a vehicle thereon, a device on said track controlled by traffic conditions, a controlling mechanism responsive to said track device, a source of energy for said controlling mechanism, a cancelling device for suspending the operation of said mechanism and means for transferring the current from said source of energy from said controlling mechanism to said cancelling device.

73. In a railway traffic controlling system, the combination of a track with a vehicle thereon, a device on said track controlled by traffic conditions, a controlling mechanism responsive to said track device, a source of energy on said vehicle for said mechanism, a cancelling device for suspending the operation of said mechanism and manually operated means for simultaneously deenergizing said mechanism and for energizing said cancelling device from said source of energy. 45
74. In a railway traffic controlling system, the combination of a track with a vehicle thereon, a device on said track controlled by traffic conditions, a controlling mechanism on said vehicle responding to said track device, a cancelling device for suspending the operation of said mechanism having an active and an inactive position, a plurality of manually operated switches remotely located from each other on said vehicle cooperatively controlling said cancelling device through independent circuits and means on said vehicle for moving said cancelling device into the active position and means whereby said track device moves said cancelling device into the inactive position. 50
75. In a railway traffic controlling system, the combination of a track with a vehicle thereon, a device on said track controlled by traffic conditions, a controlling mechanism on said vehicle responsive to said track devices, a cancelling device for suspending the operation of said mechanism and a plurality of independent circuits on said vehicle for cooperatively operating said cancelling device. 55
76. In a railway traffic controlling system, the combination of a track with a vehicle thereon, a device on said track controlled by traffic conditions, a controlling mechanism on said vehicle responsive to said track device, a cancelling device for suspending the operation of said mechanism and a plurality of sources of energy on said vehicle, and means for positioning said cancelling device by one of said sources and for holding it by the other source. 60
77. In a railway traffic controlling system, the combination of a track with a vehicle thereon, a device on said track controlled by traffic conditions, a controlling mechanism on said vehicle responsive to said track device, a cancelling device for suspending the operation of said mechanism and a plurality of sources of energy on said vehicle for operating said cancelling device, one of said sources of energy being controlled by said track device. 65
78. In a railway traffic controlling system, the combination of a track with a vehicle thereon, a device on said track controlled by traffic conditions, a controlling mechanism on said vehicle responsive to said track device, a cancelling device for suspending the operation of said mechanism and a plurality of energized circuits on said vehicle, one of said circuits energizing said controlling mechanism, means for transferring said circuit connections to said cancelling device and another of said circuits arranged to hold said device in the cancelled position. 70
79. In a railway traffic controlling system, the combination of a track with a vehicle thereon, a device on said track controlled by traffic conditions, a controlling mechanism on said vehicle responsive to said track device, a cancelling device for suspending the operation of said mechanism and a plurality of energized circuits on said vehicle, one of said circuits arranged to bring said device to the cancelling position and another of said circuits holding said device in the cancelled position and switches remotely located from each other for controlling said circuits. 75
